E. O. WILLIAMS.
HOLDER FOR ILLUSTRATED POST CARDS.
APPLICATION FILED DEO. 17, 1907.

909,497.

Patented Jan. 12, 1909.

UNITED STATES PATENT OFFICE.

ERNEST O. WILLIAMS, OF JACKSONVILLE, FLORIDA, ASSIGNOR TO PERFECTION CARD RACK COMPANY, OF NEW YORK, N. Y.

HOLDER FOR ILLUSTRATED POST-CARDS.

No. 909,497.

Specification of Letters Patent.

Patented Jan. 12, 1909.

Application filed December 17, 1907. Serial No. 406,948.

To all whom it may concern:

Be it known that I, ERNEST O. WILLIAMS, a citizen of the United States, residing at Jacksonville, in the county of Duval and 5 State of Florida, have invented certain new and useful Improvements in Holders for Illustrated Post-Cards, of which the following is a specification, reference being had to the accompanying drawings.

10 My invention relates to improvements in holders for illustrated post cards and more particularly to those constructed of wire and adapted to be interlocked with and suspended from each other in a vertical string or 15 chain.

One object of the invention is to provide a holder of this character for the storage and display of illustrated postal cards or similar articles, in which the cards will be effectively 20 supported in an upright or vertical position so that they may be readily seen.

Another object of the invention is to so construct a holder of this character that it may be made of comparatively light wire and at 25 the same time be strong and substantial enough to support a large number of cards or the like.

A further object of the invention is to provide interlocking holders of the character 30 mentioned which may be readily engaged with and disengaged from each other and which when engaged will adjust themselves so that each one hangs squarely.

With the above and other objects in view, 35 the invention consists of the features of novelty hereinafter fully described and claimed, and illustrated in the accompanying drawings, in which—

Figure 1 is a perspective view of a group of 40 my improved interlocking holders; Fig. 2 is an enlarged perspective view of one of the holders; and Fig. 3 is a vertical section through the same.

The preferred embodiment of my invention is illustrated in the drawings and is constructed of a single piece of wire of suitable size and length. This wire is bent angularly at its center as at 1 to provide a V-shaped upper central member or portion 2 at 45 the ends of the arms or branches of which are formed angular bends or seats 3, 4 which provide means of suspension for the holder. Vertical back retaining portions or members 5, 6 depend from the outer sides of the supporting or sustaining bends 3, 4 and at the

lower extremities of the portions or members 5, 6 are formed bottom supporting portions 7, 8, on which latter the cards or similar articles rest as shown in Fig. 1. At suitable points intermediate the ends of the back portions 5, 6 are formed end retaining portions or members 9, 10 which are in the form of right angular shaped arms having inner portions 11 which project horizontally or outwardly at right angles to and in the plane of the back portions 5, 6, and outer portions 12 which project forwardly from the outer extremities of the branches 11. These end retaining portions or arms 9, 10 are formed by doubling or bending the wire of which the back portions 5, 6 are constructed so as to provide upper and lower right angular branches which are united at their converging outer extremities and have their inner extremities twisted together as shown at 13 so as to give the necessary strength. The bottom portions 7, 8 are disposed in horizontal planes and at their inner ends are formed downwardly bent loops 14, 15 adapted to form seats for the reception of the bends or seats 3, 4 on the holder suspended from the one of which they form a part. The loops or seats 14, 15 are at the lower extremities of the back portions or members 5, 6 so that the weight of the several holders will be upon said portions or members and not upon the bottom portions 7, 8 as presently explained. The wire at the outer extremities of the bottom portions 7, 8 is bent upwardly and inwardly at an acute angle to provide upwardly and inwardly inclined front retaining portions or members 16, 17 which project upward a suitable distance, preferably a little short of the end retaining portions or arms 9, 10, and terminate in inwardly extending heads 18, 19 preferably constructed by bending the extremities of the wire into circular loops or rings disposed in vertical planes at right angles to the plane of the portions 2, 5, 6.

The upper holder A of the series may be 100 suspended from a wall or other vertical support by engaging its bends or seats 3, 4 with screws, nails or other suitable supporting devices or it may be suspended by a swivel or similar means engaged with said bends so 105 that the entire series of holders may be swung or turned at any angle. This upper holder supports the next lower holder B which is engaged with the former by inserting its V-shaped central member 2 between the por- 110

tions or arms 9, 10 and ends or heads 18, 19 of the portions 16, 17 and then dropping the member 2 into the loops or seats 14, 15. It will be seen that owing to the angular shape 5 of the member 2 the bends or seats 3, 4 will drop into the loops or seats 14, 15 and the lower holder will thus adjust itself upon the upper one which supports it. The next holder B and as many more as may be necessary 10 or desirable are suspended in a similar manner.

From the foregoing it will be seen that by providing the loops or seats 14, 15 at the lower end of the vertical back portions or 15 members 5, 6 the weight of the lower holders will be in a vertical line and almost entirely upon said members 5, 6 so that there will be little or no tendency of such lower holders to pull downwardly the bottom portions 7, 8 of 20 the holder which suspends them. It will be further noted that by making the front retaining or confining portions 16, 17 as shown, that is, so that they project upwardly and inwardly at a slight angle and have the heads 25 or enlargements 18, 19 at their upper ends, the cards in such holder will be yieldably pressed against the back portions or members 5, 6 so that they will be supported in a vertical position and cannot tilt so as to prevent 30 them from being readily seen when the holder is on a level with or below the eye. The provision of the inwardly projecting heads or enlargements 18, 19 cause the cards to be engaged at two points only by the front 35 retaining portions so that they may be more readily removed and there will be less danger of scratching or marring the cards. By constructing the end retaining portions or members 9, 10 as shown and disposing them upon 40 the back members 5, 6 it will be seen that the device will be much stronger and more rigid than if they were carried by the front portions or members 16, 17.

By making the holder as above described 45 it may be constructed of much lighter wire than it is necessary to use in the construction of similar devices heretofore produced.

It will be understood that while I preferably make the holder of a single piece of wire 50 it may be otherwise constructed.

Having thus described my invention what I claim is:

1. A holder of the character described formed of wire and having straight upright 55 back portions 5, 6, front portions, bottom portions uniting the front and back portions, and the V-shaped central member 2 having its lowest point at its center and the diverging arms inclined upwardly and outwardly 60 from said center and connected by the bends 3, 4 to the upper ends of the back portions 5, 6, substantially as and for the purpose specified.

2. A holder of the character described, 65 formed of wire and having supporting bends

or seats, front and back portions united by bottom supporting portions and angular end retaining portions formed upon the back portions intermediate their ends.

3. A holder of the character described, 70 formed of wire and having supporting bends or seats, vertical back portions, horizontal bottom supporting portions and resilient front retaining portions inclined inwardly and upwardly and having at their upper ends 75 heads to provide single points of contact for cards or other articles.

4. A holder of the character described, 80 formed of wire and having supporting bends or seats, vertical back portions terminating in the downwardly turned loops or seats 14 and 15 to receive the supporting bends or seats of the succeeding holder, the horizontally disposed bottom portions projecting 85 forwardly from the loops or seats 14 and 15 and resilient front retaining portions inclined 90 inwardly and upwardly from said bottom portions and having their upper ends formed with inwardly projecting heads to provide single points of contact for the front faces of 95 the cards, substantially as set forth.

5. A series of holders of the character described each formed of wire and having vertical back portions, a V-shaped central member having diverging arms inclined upwardly 95 and outwardly from its center to its outer ends, supporting bends or seats uniting the latter to the back portions, upright front portions, horizontal bottom portions projecting inwardly from the front portions, and the 100 downwardly bent loops or seats uniting the bottom portions and the lower ends of the back portions and adapted to receive the supporting bends or seats of the succeeding holder, substantially as set forth.

6. A holder of the character described formed of wire and having supporting bends or seats, vertical back portions, horizontal bottom portions 7, 8, resilient front retaining portions 16, 17, inclined upwardly and inwardly from the outer ends of said horizontal bottom portions, said front portions being independent of each other and disposed opposite said back portions, and the inwardly projecting heads 18, 19 at the upper ends of 110 said front portions, said heads projecting inside of the plane of the front portions and adapted to provide single points of contact for the front faces of the cards and the other articles in the holder, substantially as set 115 forth.

7. A holder of the character described, 120 formed of wire and having supporting bends or seats, vertical back portions, right angular end retaining portions arranged intermediate the ends of said back portions and formed by doubling and bending the latter, front retaining portions and bottom supporting portions uniting the front and back portions.

8. A holder of the character described, formed of a single piece of wire bent angularly at its center to provide a **V**-shaped central member having at the ends of its diverging arms angular supporting bends or seats, vertical back portions depending from the latter and having their intermediate portions bent to provide outwardly projecting right angular end retaining portions or members, horizontal bottom supporting portions projecting outwardly from the lower ends of the vertical back portions and united thereto by downwardly bent loops or seats to receive

the supporting bends or seats of the succeeding holder, and upwardly and inwardly inclined front retaining portions rising from the bottom portions and having their upper ends bent to provide inwardly extending contact loops, substantially as and for the purpose set forth. 15

In testimony whereof I hereunto affix my signature in the presence of two witnesses.

ERNEST O. WILLIAMS.
